UNITED STATES PATENT OFFICE.

FRANK ROBERTSON, OF DAYTON, OHIO.

SHELL.

1,211,626.

Specification of Letters Patent.

Patented Jan. 9, 1917.

Application filed July 2, 1915. Serial No. 37,729.

To all whom it may concern:

Be it known that I, FRANK ROBERTSON, a citizen of the United States, residing at Dayton, in the county of Montgomery and 5 State of Ohio, have invented certain new and useful Improvements in Shells, of which the following is a specification.

My invention relates to ordnance and more particularly to an explosive projectile 10 of the percussion type.

An object of the invention is to provide a shell or projectile wherein the explosive substance and a suitable percussion device are so related or relatively arranged that 15 the impact incident to contact of the shell with a resisting object will cause the device to move forcibly into engagement with said explosive substance and by such engagement cause the shell or projectile to explode.

In describing my invention in detail reference will be had to the accompanying drawings wherein like characters denote like or corresponding parts throughout the several views, and in which:—

Figure 1 is a longitudinal sectional view of my improved explosive shell. Fig. 2 is a section of the line 2—2 of Fig. 1. Fig. 3 is a section of the line 3—3 of Fig. 1. Fig. 4 is a section of the line 4—4 of Fig. 1. Fig. 5 is a section of the line 5—5 of Fig. 1.

Referring now to the drawings by numerals, 1 designates as an entirety, the shell or projectile, tapered at one end and recessed 35 or furrowed as indicated at 2, to provide transverse cutting edges 3 which, upon contact of the shell with a resisting object, will cause said object to be split or divided to a greater extent than would ordinarily or 40 otherwise be the case.

The shell 1 in its preferred embodiment is made up of two shell sections, designated respectively 4 and 5. Shell section 4 is hollow and open at one end to receive a complementary core or extension 6 integral with 45 the shell section 5. The diameter of the core in the shell section 4 is reduced at its forward end to provide an annular shoulder 7, interiorly of the shell, which shoulder 50 7, upon contact with a resisting object, will engage a like shoulder 8 formed on the core 6 in proximity thereto.

An elastic ball 9 (preferably of rubber) is located in the core of the shell and at the

forward end thereof, which ball in actual 55 practice, is adapted to contain a highly explosive substance such as nitro-glycerin, gun cotton or the like. Core 6 is longitudinally bored as indicated at 10, to receive a percussion device 11. The said device 11 at its 60 forward end is tapered and pointed as indicated at 12, the point being normally in contact with the ball 9, the contact being insufficient to depress or in any way indent the yielding material of which the ball is composed. A stem 13 is formed upon the percussion device 11 at the opposite end from that designated 12, which stem fits a reduced extension of the bore 10, designated 14. Lead babbitt 15 is utilized to engage 70 with and hold the pointed terminal of the percussion device 11, it having been found, upon test, that a soft metal such as lead babbitt will so grasp and hold the said percussion device as to preclude accidental displacement in transporting the projectile from place to place and in ordinary handling, yet release the percussion device should the projectile subsequent to firing, contact with a resisting object intended as 75 its mark.

Section 5 of the shell is recessed as at 16, to afford a space within which powder or the like explosive substance may fit in loading the gun or mortar used to fire the shell. 85

In use, the projectile or shell is fired and upon contact of the tapered end of the shell with a resisting object, the said object is split or divided. The impact or contact of the shell with said object will cause the percussion device 11 to be dislodged from engagement with the retaining element 15 and to move bodily forwardly into forced contact with the yielding elastic ball 9. Such forced contact or engagement of the device 95 with the ball will cause the explosive substance therein to be set off and exploded and the entire shell to be scattered that damage by shrapnel may result.

Having thus fully described my invention 100 what I desire to secure by Letters Patent is:—

A projectile including a hollow shell comprising complementary shell sections, a yielding ball containing an explosive substance 105 disposed forwardly and interiorly of the shell, one of the shell sections engaging the ball to act as a retaining means therefor, a

longitudinally movable percussion device mounted interiorly of the shell, one end of said device normally contacting the mentioned ball, means to releasably maintain the percussion device against movement, said device being movable forcibly into contact with the ball and the explosive substance therein incident to contact of the pro-

jectile with a resisting object, substantially as described.

In testimony whereof I affix my signature in presence of two witnesses.

FRANK ROBERTSON.
